APPARATUS FOR TREATING MATERIAL
WITH A GAS

Alex W. Arnold, La Crosse, Wis.

Application July 10, 1944, Serial No. 544,287

6 Claims. (Cl. 34—57)

1

This invention relates to improvements in apparatus for treating material with a gas.

A primary object of the invention is the provision of a novel and improved simplified and compact apparatus having novel means for repeatedly subjecting the material to be treated to blasts of treating gas. While the apparatus is primarily intended for dehydration, it may be used for other treating operations.

The invention further has as its object the provision of a temperature changing chamber with reference to the treating chamber, the whole being so compactly organized that the apparatus may readily be made portable if desired.

A further object of the invention is the provision of a novel construction of the treating cylinder, in which a helical flange or screw advances the material through the cylinder, successive blasts of gas being peripherally admitted and the arrangement being such that power is economized because the cylinder or drum is free of lifting baffles and the material to be treated is not required to be lifted to any great distance in traversing the cylinder.

A further object is to provide a novel and compact dehydrator, in which heat is economized and fully used for dehydration.

Other objects will appear more sufficiently from the following disclosure of the invention.

In the drawings:

Fig. 1 is a view partially in side elevation and partially in longitudinal section through a device embodying the invention.

Fig. 2 is a view in end elevation of the apparatus shown in Fig. 1.

Fig. 3 is a detailed view taken through the apparatus in cross section.

Fig. 4 is fragmentary detailed view of the treating cylinder in perspective.

Fig. 5 is an enlarged fragmentary detail showing a partial cross section of the treating cylinder on a larger scale than that of Fig. 3.

Fig. 6 is a fragmentary section taken on the line 6—6 of Fig. 5.

Like parts are denoted by the same reference characters throughout the several views.

By way of emphasizing the compactness of my improved device, I have chosen to exemplify its construction by illustrating a portable embodiment. The shell or casing 7 together with

2

platform 8 comprise a frame supported at the rear by a wheeled axle 9 and at the front by a dirigible axle 10. The flanged rollers 11 at the front and 12 at the rear of the casing support the rings 13 and 14 on the treating drum or cylinder 15 for rotation. Annular packing of asbestos or the like is carried at 16 and 17 on the casing to engage the periphery of the drum so that the drum may rotate on the rollers without permitting any substantial communication of atmospheric air about the drum with the gases in the interior of the casing. To rotate the drum, I may employ a motor 18 connected through a reducing gear set 19 with one of the rollers 11. This roller may, in turn, be connected by chain 20 with the other roller 11.

The material to be treated is admitted through an elbowed hopper 21 equipped with a conventional rotary charging valve 22 driven by a belt 23 from the reducing gear set 19. At the other end of the drum a discharge throat 24 guides the material to the inlet of a fan casing 25 within which a rotor 26 is driven from motor 21. The discharge pipe 28 from the fan leads to the conventional separator 30, which discharges the treating gas at 31 and the material at 32.

The drum is provided interiorly with a substantially continuous helical flange at 33 which, as the drum rotates (clockwise as viewed in Fig. 3), progressively advances the work through the drum from its inlet end at the right in Fig. 1 to its discharge end at the left in Fig. 1. The helical channel between successive turns of the flange 33 is provided at intervals with louvers 36 through which gases from the casing 7 are admitted to the interior of the drum 15. According to the requirements, these louvers may be few in number or may be numerous. In the drum illustrated, the channel is provided with about six louvers or inlet apertures per convolution near the inlet end of the drum but, after about three turns or convolutions, the number of louvers is reduced gradually until there are only about three louvers per convolution near the outlet end, the object being (with particular reference to a dryer) to dry the material rapidly while it is very wet, but to protect it from overheating as it becomes dry.

In order to provide the inlet louvers at 36, I make the periphery of the drying drum 15 in the form of a series of volute wall sections 37, each

of which approaches approximately tangentially the periphery of the flange 35. These volute sections preferably lap somewhat, as clearly shown in Fig. 3, so that, as the drum rotates clockwise, the material confined between successive turns of the helix 35 and dropping from the rear margin 38 of each successive volute wall 37 will be caught by the next successive volute wall, as indicated at 39. In falling from the rear margin 38 of one volute wall section on to the next succeeding wall section, the material will traverse the blast of treating gas admitted through one of the openings 36. It will also be continuously exposed to a whirling current of such gases, such current being maintained at all points within the drum by the general tangential admission of such gases through the louvers 36 and the axial withdrawal of such gases by the blower fan 26.

The interior of casing 7 provides a plenum chamber in which the treating gases are maintained available at all times for passage through the several louvers 36 to the interior of the drum. The chamber has a bottom wall at 40 and a false bottom or partition at 41, the latter (for dryer purposes) preferably supporting a layer of fire-brick at 42 and a combustion chamber 43 which may conveniently be made from a semi-tubular section of cast pipe, notched at 44 to provide an outlet into the plenum chamber within which the drying cylinder 15 rotates. (For other purposes, other temperature changing or gas modifying means would be substituted for the heating or combustion chamber.)

In the end of the casing 7 is an admission port 45 controlled by valves 46. Air admitted past the valves 46 traverses the space between the bottom 40 and the partition 41 until it reaches the end of the partition. Such air picks up most of the heat which might otherwise be lost through downward radiation. Passing about the end of the partition 41 the air enters the interior of the combustion chamber. At this point, the burner 47 projects into the end of the combustion chamber, being preferably supplied with its own air by means of blower 48. The resulting flame is projected lengthwise of the combustion chamber and the products of combustion are thoroughly mixed with the air supply admitted through the port 45 and raise the temperature thereof. Heat radiated from the wall 43 of the combustion chamber is delivered to the interior of the casing 7 and thereby saves fuel used in the dehydration operation.

The fact that the combustion chamber and the air admission duct are within the casing 7, and in the same chamber in which the drying drum operates, makes the device not merely compact but very economical of heat.

Although the gases and the material to be treated preferably move in the same direction through the drum, the advance of the material is almost quite largely controlled by the rate of drum rotation and the pitch of the helical partition 35. Complete treatment is assured inasmuch as the apparatus exposes not only the freshly admitted product, but the product in all stages of treatment, to gases which have not previously acted thereon. Even when the material is almost ready for discharge, there will still be a few of the louvers 36 across which the material must fall, exposed to newly admitted gas.

I claim:

1. In a device of the character described, a drum having an inlet and an outlet for material to be treated and provided interiorly with a heli-

cal flange and having louvers opening substantially tangentially of the periphery of the flange into the drum only at points disposed between successive convolutions of said flange.

2. In a dryer, a drum having an inlet and an outlet for material to be treated and provided interiorly with a helical flange and having louvers opening substantially tangentially of the periphery of the flange into the drum only at points disposed between successive convolutions of said flange, a casing in which said drum is mounted for rotation, said casing providing a plenum chamber for supplying dehydrating gases for entry into said drum through said louvers, means for establishing a pressure differential for the flow of gas from said plenum chamber into said drum, said louvers opening into said drum in a direction opposite to the direction of drum rotation whereby material in the drum will fall by gravity across successive louvers exposed to dehydrating gases entering the drum.

3. In a device of the character described, the combination with a casing, of a drum having an inlet and an outlet for material to be treated and rotatably mounted therein and having its ends projecting from the casing, said drum being provided interiorly with a helical flange and peripherally with volute wall portions inlapping relation to afford louvers in helical series disposed wholly between successive flights of said flange and opening from the casing into the drum substantially tangentially of the periphery of the flange, means for delivering into one end of the drum material to be treated therein, means for rotating the drum in a direction opposite to the direction of tangential admission of gas thereto from the casing, means for exhausting from the opposite end of the drum gas which has acted on material therein, and means in the casing for heating gas for acting on such material, said casing comprising a plenum chamber from which gas is admitted to the drum through the several louvers aforesaid.

4. Apparatus of the character described, comprising in portable compact form a frame, a casing thereon having apertured ends, a drum having an inlet and an outlet for material to be treated and rotatably mounted in the casing and having its ends projecting from the casing apertures, said drum comprising a helical flange having segmental projections outside the drum and providing within the drum a helical channel therethrough, and mutually lapping volute peripheral wall portions disposed between successive flights of the flange and marginally connected to said projections to provide louver passages opening into the drum between successive flights of said flange, an inlet fitting connected with one end of the drum for delivering thereto material to be treated therein, a discharge fitting connected with the opposite end of the drum, a blower casing having an inlet with which said discharge fitting communicates, a separator mounted on said frame, a delivery pipe leading from said blower casing to said separator, means for rotating the drum in a direction opposite to the direction of tangential admission of gases from the casing to the drum through said louvers, the lapping of said volute wall portions being adapted to deliver material from said wall portions to successive wall portions of the drum across the louvers in the course of drum rotation, and said casing comprising a plenum chamber about the drum from which gases are sup-

plied for admission through said louvers for the treatment of such material.

5. The device of claim 4, in which said casing is interiorly provided with temperature changing means, and means for admitting gases to be changed as to temperature for distribution in said plenum chamber for the treatment of material in said drum.

6. A drum of the character described comprising a helical flange having its successive flights radially disposed and provided on its exterior periphery with segmental tooth-like outward projections, said drum having mutually lapping peripheral wall portions disposed between successive flights of the flange and marginally connected to said projections to provide louver passages opening into the drum between successive flights of the flange.
